BUFFING WHEEL

Fritz E. Hendrickson, South Elgin, Ill., assignor
of one-half to Murray Ireland, Elgin, Ill.

Application March 23, 1946, Serial No. 656,587

4 Claims. (Cl. 51—193)

1

My invention relates to buffing wheels.

An object of my invention is to provide a novel assembly of parts constituting a composite buffing wheel.

Another object of my invention is to provide a buffing wheel that shall be operative by an inexperienced man to give better results than obtainable heretofore by an experienced man.

Other objects of my invention will either be evident from a description of one form of device embodying my invention or will be pointed out during the course of such description and set forth in the appended claims.

In the drawings,

Figure 1 is a planar view of a section of my improved buffing wheel comprising a plurality of plies.

Fig. 2 is a side elevational view of one metal supporting disc,

Fig. 3 is a side elevational view of another metal supporting disc,

Fig. 4 is a sectional view on the line 4—4 of Fig. 1,

Fig. 5 is a cross sectional view taken on the line 5—5 of Fig. 6,

Fig. 6 is a view in side elevation of the section of plies shown in Fig. 1 after having been folded on a diametral line and stitched,

Fig. 7 is a view, in front elevation, of the discs shown in Figs. 2 and 3 when in assembled position,

Fig. 8 is a top plan view of Fig. 6,

Fig. 9 is an assembled view of a buffing wheel embodying my invention,

Fig. 10 is a fragmentary view, in front elevation, showing the mounting of a section on the supporting discs,

Fig. 11 is a fragmentary sectional view taken on the line 11—11 of Fig. 10, and

Fig. 12 is a section taken on the line 12—12 of Fig. 9.

Referring first of all to Fig. 1 of the drawings, I have there shown a section 21 of buffing wheel embodying my invention and comprising a plurality of individual substantially oval-shaped plies 23 which may be of cotton cloth. A plurality of such plies about 4 in number may be assembled by being placed one upon the other after which two seams 25 and 27 are provided extending substantially from one side of said plies to the other side at about one-half the distance from the center of the substantially oval ply and the periphery. Each of the plies 23 is provided with an elongated center opening 29 therethrough and a reinforcing member 31, made

2

of heavier cloth than are the plies 23, is secured against one side of the set of plies by a plurality of seams 33.

The number of plies which are held together by 5 seams 25, 27 and 33 may vary widely, but I have found that if I place four such plies together and then lay on said four plies a plurality of threads 35 of fibrous material, such as sisal or Tampico, then place on said four plies and threads another 10 set of four plies, after which I may place another set of threads 35 which are more or less uniformly spaced apart and then place another set of four plies on top of the other two sets and the two sets of threads 35, I obtain a buffing wheel embodying my invention. The inner opening 29 is 15 of elongated shape and the threads 35 of sisal or other similar fibrous material extend substantially at right angles to the longer dimension of opening 29. The sisal threads 35 located at substantially the middle portion of member 31 may be so bent as to avoid covering the opening 29.

I then fold the assembled sets of pluralities of 20 plies on a diametral line which extends substantially at right angles to the threads 35 and obtain thereby a folded section substantially as shown in 25 Fig. 6 of the drawings. I then provide a plurality of seams 37, 38 and 39 which hold together the adjacent folded halves, the seams 37 and 39 extending well toward the diametral line of the 30 folded plies.

I provide means for supporting a plurality of such folded sections, said means comprising a pair of discs 41 and 43, each provided with a plurality of hook members 45. The hook members 45 extend beyond the outer periphery of the discs 41 and 43 and the hooks on disc 41 extend all in one direction while the hooks on disc 43 extend in the opposite direction. Means are provided for holding the two discs 41 and 43 in adjacent fixed position which may comprise a pin 47 in disc 43 which is adapted to fit into a corresponding opening 49 in disc 41 after the desired plurality of sections of the buffing wheel have been placed in proper operative position on the 45 adjacent pairs of hooks which are positioned as shown in Fig. 7 of the drawings. The assembled position of said folded sections is shown in Fig. 9 of the drawings.

Fig. 9 of the drawings shows the mounting of 50 five such sections upon the discs, it being understood that in this assembly the right-hand end portion of each section will abut the left-hand end portion of the next adjacent section.

In the assembly of a plurality of sections 21 on 55 a pair of discs 41 and 43, the two metal discs are

placed one on top of the other, with the hooks resting one above the other and extending in opposite directions after which sections 21, shaped as shown in Fig. 6, are placed around the discs. The individual sections are then moved radially inwardly so that the hooks 45 enter the elongated openings 29, after which the two discs are moved so that the cooperating pairs of adjacent hooks will take the positions shown in Figs. 7, 9 and 10 when the pin 47 will enter opening 49. The pairs of hooks will thus hold the plurality of plies 23 in their proper operative position against the outer periphery of the discs 41 and 43 against the action of centrifugal force during operation.

Referring now to Fig. 12 of the drawings, I have there illustrated the mounting of three such assembled sets of sections upon a shaft 51. This shaft is provided with a disc 53 which is adapted to support the sections and with a second supporting disc 55 which latter may be tightly clamped in place as by a nut 57 having screw-threaded engagement with the outer end portion 59 of the shaft 51. It is to be understood that the outer end portion 59 of shaft 51 is of reduced diameter to provide an abutting portion thereon for supporting disc 53.

The buffing wheel embodying my invention is particularly useful for the bright polishing of steel objects although its use is not limited thereto. I have found by repeated tests that a buffing wheel of the kind hereinbefore described will provide a high polish on nickel-plated steel which is to be chrome plated and which is to have a high polish.

While I am of the opinion that the use of the threads of sisal or of other similar fibrous material is of benefit, without deleterious action of the threads of fibrous material, nevertheless I have found that buffing wheels embodying my invention are of greater value in polishing the ordinary mat surfaces of nickel-plated steel.

Various modifications may be made in the device embodying my invention without departing from the spirit and scope thereof and all such modifications coming clearly within the scope of the appended claims shall be considered as part of my invention.

I claim as my invention:

1. A composite buffing wheel comprising a plurality of buffing sections, each section comprising a plurality of sets of centrally perforated cloth discs in close side-by-side position, a plurality of sets of parallel threads of fibrous material between each two adjacent sets of discs, a plurality of seams extending across all of said sets of discs, each plurality of sets of discs being folded diametrically at right angles to said threads of fibrous material and a pair of seams substantially

parallel to said first named seams holding together said folded portions.

2. A composite buffing wheel comprising a plurality of individual buffing sections, each section comprising a plurality of sets of centrally perforated cloth discs in close side-by-side position, a plurality of sets of parallel threads of fibrous material between each two adjacent sets of discs, the length of said sets of threads being substantially equal to the width of that part of the disc engaged by said sets of threads, a plurality of substantially straight seams extending through all of said sets of discs parallel to said sets of threads, each plurality of sets of discs being folded diametrically at right angles to said threads and a pair of seams extending substantially parallel to said first named seams and holding together said folded portions.

3. A composite buffing wheel comprising a plurality of buffing sections, each section comprising a plurality of sets of centrally-perforated cloth discs in close side-by-side position, parallel threads of fibrous material having a length substantially equal to the width of that part of the disc engaged by said threads, a plurality of substantially straight seams extending across all of said sets of discs substantially parallel to said threads, each plurality of sets of discs being folded diametrically at right angles to said threads, a pair of spaced seams holding together said folded portions and extending substantially parallel to said first mentioned seams, a piece of relatively heavy cloth around said central perforation and seams holding said heavy cloth against one side of said section.

4. A buffing wheel comprising a plurality of buffing sections adapted to be supported by a metal disc adjacent to the outer periphery thereof, a plurality of hook members on said disc engaging said sections, each section comprising a plurality of sets of centrally perforated cloth discs in close side-by-side position, a plurality of parallel threads of fibrous material between each two adjacent sets of discs, the length of said threads being substantially equal to the width of that part of the disc engaged by said threads, a plurality of substantially straight seams of thread extending through all of said sets of discs substantially parallel to said threads and confining them, each plurality of sets of discs being folded diametrically at right angles to said threads, a pair of seams extending substantially parallel to said first named seams and inwardly from the periphery of said discs and holding together said folded portions, said hook members on said metal discs interfitting with said central perforations to hold said sections with their ends overlapping the adjacent sections.

FRITZ E. HENDRICKSON.
